(57) **CLAIM**

The ornamental design for a portable game assembly, as shown and described.

DESCRIPTION

FIG. 1 is a perspective view of the portable game assembly of the instant invention in an open position;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is a perspective view of the portable game assembly thereof in a closed position.

The broken lines and indicia shown in the drawings are not part of the claimed design and are shown for illustrative purposes.
